(57) **CLAIM**

The ornamental design for a skate wheel nut, as shown and described.

DESCRIPTION

FIG. 1 is a front perspective view of the skate wheel nut according to my design;

FIG. 2 is a rear perspective view of the skate wheel nut;

FIG. 3 is a front elevation view of the skate wheel nut;

FIG. 4 is a rear elevation view of the skate wheel nut;

FIG. 5 is a right-side view of the skate wheel nut;

FIG. 6 is a left-side view of the skate wheel nut;

FIG. 7 is a bottom view of the skate wheel nut;

FIG. 8 is a top view of the skate wheel nut; and,

FIG. 9 is a front perspective view of the skate wheel nut in a position of use thereof.

The broken lines showing the user's hand, the portions of the skate tool, the skate wheel, and the portions of the truck of the skateboard form no part of the claimed design.
